ATTORNEYS.

UNITED STATES PATENT OFFICE.

CORNELIUS R. UMBENHOWER, OF ANDERSON, INDIANA.

VAPOR OIL-BURNER.

1,329,445.

Specification of Letters Patent.

Patented Feb. 3, 1920.

Application filed October 18, 1919. Serial No. 331,649.

To all whom it may concern:

Be it known that I, CORNELIUS R. UMBENHOWER, a citizen of the United States, and a resident of Anderson, county of Madison, and State of Indiana, have invented a certain new and useful Vapor Oil-Burner; and I do hereby declare that the following is a full, clear, and exact description thereof, reference being had to the accompanying drawings, in which like numerals refer to like parts.

This invention relates to vapor oil burners and is an improvement on the invention shown in Patent No. 827,764, dated

15 August 7, 1906.

The object of this invention is to provide, by the rearrangement of the parts and the addition of air vents, for the complete combustion of the fuel in the structure described

20 in the before mentioned patent.

The full nature of this invention will be understood from the accompanying drawings and the following description and claims.

25 In the drawings Figure 1 is a central cross section of the improved oil burner taken on the line 1—1 of Fig. 2. Fig. 2 is a plan view of the burner with the reflecting means omitted.

30 In the drawings 10 indicates a pipe leading from any suitable supply of oil, such as kerosene or the like. 11 is a pipe leading therefrom horizontally and then vertically into the burner. A valve 12 is provided for controlling the supply of fuel to the burner. The vertically projecting portion of the pipe 11 is threaded at its upper end to receive the dome 13, the same having an upwardly extending rim 14 concentric therewith and a discharge outlet 15 in the center thereof. The dome, while hollow, is rather thick and solid, especially in the upper portion, so that it will hold considerable heat, and about its base there is a series of vertical air holes 9.

Under the dome 13 there is a dripping-pan 16, preferably scalloped at 17 so that air may pass freely from the front of the stove in which the burner is located. In the center of the dripping-pan there is a central hole 18 through which the pipe 11 extends. Four stands or supports 19 are spaced an equal distance from each other in the dripping pan 16, and notched or shouldered to receive and support what may be termed an oil ring or oil pan 20, which is

cylindrical and has an outer upwardly extending rim 21 and an inner upwardly extending rim 22 carrying a pipe guide 23, through which the upper portion of the pipe 11 extends. Air passages 24 are provided between the inner rim 22 and the pipe guide 23 by the guide supporting portions 25. The oil ring 20 is also provided with a plurality of air openings 26 herein shown in the form of tubes.

The outer and upper edge of the ring 20 is suitably grooved to receive and support a casing 27, the same having a flared lower portion and an enlarged upper portion 28 providing a combustion chamber 29. A perforated heating plate 30 is supported by the casing 27, and the same is provided with a plurality of small outlet holes 31 and a pair of large outlet openings 32, one at each end. These latter openings are covered by deflectors 33 that are supported on legs 34, the same being notched at their lower ends to rest loosely within the openings 32 and on the top of the plate 30. The casing 27 is provided with a pair of openings 35 registering with the openings 32, to provide for the introduction of additional air in the combustion chamber 29. The dripping pan 16 has two openings 36 provided in its base, and threaded in said openings are the tubes 37 extending upwardly into communication with the combustion chamber 29 through the openings 35.

From this description it is observed that the oil burner is provided with a plurality of air passages for vaporization and partial combustion of the fuel, and in addition there is provided the auxiliary air tubes 37 which supply oxygen to the flame in the mixing and combustion chamber 29 at a point where the flames are coolest. This provides for the complete combustion of the fuel before the flames pass out through the openings 32.

Herein it will be observed that the central opening 18 not only supplies air to the combustion chamber through the passages 9 and 24, but also supplies air to the tubes 26 as shown by the arrows in Fig. 1. With this construction a better draft through the tubes 26 and the air passages 24 is secured. The operation of the device is the same as that shown in the patent hereinbefore mentioned, the oil running down the dome 13 into the rim 14 and thence into the oil ring 20. The fuel is ignited by a flame being presented to either the openings 32, 31 or 18. The burn-

2

ing fuel in the oil pan 20 will soon heat the upper end of the pipe 11 and the dome 13 sufficiently to vaporize the oil as it passes out through the discharge opening 15 whereupon the oil will not flow more than half way down the dome 14 before it is entirely vaporized. The air for causing the combustion, as briefly described, is furnished by the air passages 9, 24 and 26, and the additional supply for complete combustion is furnished at the point where the flame is coolest by the tubes 37.

The invention claimed is:

1. An oil burner comprising means for supplying oil thereto, a dome having an outlet therein and a portion over which the oil may flow, an oil pan concentric with the dome and having a plurality of upwardly extending tubes for the admission of air, a casing concentric with and surrounding said dome and enlarged at its upper end to form a combustion chamber and having an air-opening therein, a heating plate surmounting said casing and closing the same, said plate having a flame opening therein, a drip pan supporting said oil pan, said drip pan having an air-opening therein, and means connecting said air openings in the drip pan and the casing.
2. An oil burner comprising means for

supplying oil thereto, a dome having a discharge outlet and providing a vaporizing surface for the fuel, an oil pan concentric with the dome and having a plurality of openings therein for the admission of air, a casing surrounding said dome and having an enlarged portion providing a combustion chamber, a plate having a flame opening and closing said chamber, said casing having an air opening therein registering with said flame opening in said plate, and tubular means secured in said casing air-opening and extending downwardly therefrom.

3. An oil burner comprising means for supplying oil thereto, a dome having a discharge outlet and a portion over which the oil may flow and be vaporized, a casing surrounding said dome and providing a combustion and mixing chamber therein, an oil pan concentric with said dome and beneath the same, said pan having a plurality of openings therein for supplying air to the mixing and combustion chamber, and a plurality of tubes extending downwardly from said casing for providing an additional supply of air to the combustion chamber for the complete combustion of the fuel.

In witness whereof, I have hereunto affixed my signature.

CORNELIUS R. UMBENHOWER.
